UNITED STATES PATENT OFFICE.

WILLIAM L. HAYNES, OF BURLINGTON, NEW JERSEY, ASSIGNEE TO UNITED STATES CAST IRON PIPE & FOUNDRY COMPANY, OF BURLINGTON, NEW JERSEY, A CORPORATION OF NEW JERSEY.

CENTRIFUGAL PIPE MOLD.

Application filed March 9, 1923. Serial No. 542,361.

To all whom it may concern:

Be it known that I, WILLIAM L. HAYNES, a citizen of the United States of America, and resident of Burlington, county of Burlington, State of New Jersey, have invented certain new and useful Improvements in Centrifugal Pipe Molds, of which the following is a true and exact description, reference being had to the accompanying drawing, which form a part thereof.

My invention relates to the construction of centrifugal pipe molds in which the metal comes into direct contact with the metal of the mold and which molds are so formed as to cast a bell flange or enlargement on the end of the pipe. As heretofore constructed, such molds have been made of an integral steel forging and the provision and machining of the bell portion of such molds has added largely to the expense of manufacture. Centrifugal pipe molds are subject to deterioration from two causes, first, by erosion or attrition of the barrel in the cylindrical portion of the mold which results from the mechanical abrasion of dragging the newly cast pipe lengthwise of the mold to get it out of the mold, and to provide in the best way for such attrition the barrel or cylindrical portion of the mold should be made of steel of such composition and so heat treated as to be very hard and resistant to abrasive action. With regard to the bell portion of the mold, however, this portion of the mold will have sufficient draft to be substantially free from contact with the pipe as it is being drawn out of the mold, but the interior surfaces of the bell portion of the mold are subjected to strains caused by stresses due to expansion and contraction and these stresses have a tendency to ultimately cause heat cracks in the bell, such cracks having a tendency to form both parallel to the cast of the mold and also in rings concentric with the mold. The object of my invention is to provide a centrifugal mold in which the cost of manufacture will or may be less and in which the barrel and bell portions of the mold will be made of materials best adapted to resist the deteriorating influences to which they are subjected and I accomplish this by forming the barrel and bell portions of the mold of separable parts each of which can be formed and treated by such material

and in such a way as to be most resistant to the peculiar strains to which the parts are subjected. By preference, I make both parts of the mold of steel, the steel used for the barrel being of such composition and so heat treated as to be highly resistant to the abrasive action of the pipe drawn through it and the steel of which the bell section is made being of such composition and so heat treated as to be much softer and more resistant to the stresses due to expansion and contraction. I prefer to make both sections of the mold of steel for the reason that I thus provide for substantial uniformity in contraction and expansion under varying heat conditions, which is of obvious importance as bearing on the tightness of the joint at the places where the two sections of the mold are united together but obviously metals other than steel can be used particularly in the formation of the bell section and obviously, also, this section can be cast instead of forged with a considerable saving in cost of manufacture.

Reference being now had to the drawing which illustrates my invention and which is a vertical section through a mold and pertinent parts, the above construction of the mold and of the parts shown in connection with it being similar to that shown in the de Lavaud Patent Number 1,299,918, of April 8, 1919.

In the drawing, A indicates the framing of the machine which is provided with tracks indicated at A' on which rest the supporting wheels C of the casing indicated at B. At the right hand end of the casing is a rotatable end piece indicated at E running in ball bearings F secured at the end of the casings, and having, as shown, packings at G, G', the packing at G' being between the rotatable end piece E and a separate wall H secured to the casing and forming with the rotatable end piece E a turbine chamber J in which runs the turbine indicated at I to which is secured the rotatable part E. H' is also a rotatable end piece running in a ball bearing F at the left hand end of the casing and having a packing as indicated at G'. K and K' are the two parts of my centrifugal mold, the part K making up the cylindrical barrel of the mold and the part K' the bell end of the mold. These parts may be secured together

in any convenient way which will insure a tight joint on the inside of the mold. As shown, the right hand end of the barrel K is internally recessed and threaded, as indicated at K², and formed with an abutting surface as indicated at K³. The end of the bell end is externally threaded to thread with the portion K² as indicated at K⁴ and is formed with an end abutment K⁵ adapted 10 to fit tightly against the abutting surface K³, as shown. The bell end of the mold is, as shown, formed with a flange K⁶, by which it can be firmly secured to the rotating end piece E and it is also formed, as shown, 15 with perforated lugs K⁸ for a purpose to be described. The left hand end of the barrel section K is, as indicated at K⁷, adapted to fit and be attached to the end piece H'. L indicates a core supporting ring on which 20 is formed the core indicated at N. The ring L is fitted in the mouth of the bell section and secured in place by the wedges M passing through the perforated lugs K⁸. O is a ring secured to the end of the mold most 25 conveniently, as shown, by screws attaching it to the end piece H', this ring having a portion indicated at O' which forms the end section of the mold.

While, as I have stated, the general make 30 up of the mold and associated parts is similar to that shown in the de Lavaud Patent 1,299,918, it will be understood that it is intended for use with the spout through which molten iron is introduced into the mold in

the manner described in the de Lavaud Patent 35 1,329,295 of January 27, 1920.

While I have in the drawings shown the turbine H arranged for rotating the mold as described in the de Lavaud patent of April 8, 1919, it will, of course, be understood that the method by which the mold is rotated is, so far as my present invention is concerned, entirely immaterial, the invention being strictly limited to the described construction of the mold in two parts in the 40 45 manner and for the purpose which has been sufficiently described.

Having now described my invention, what I claim as new and desire to secure by Letters Patent, is:

1. A centrifugal mold for casting bell flange or enlarged ended pipe consisting of an integral forged cylinder of hard steel in combination with a separable metal end piece having the internal form of the bell end of 50 55 the pipe and formed of a softer steel.

2. A centrifugal mold for casting bell ended pipe, consisting of an integral metal cylinder having one end screw threaded and formed with an annular seat at the end, in combination with a separable metal end piece having the internal form of the bell end of the pipe, said end piece having its smaller end threaded and formed with a shoulder adapted to fit against the shoulder 60 65 of the cylindrical section when screwed to it.

WILLIAM L. HAYNES.
